UNITED STATES PATENT OFFICE.

GEORGE E. MIRFIELD, OF YOUNGSTOWN, OHIO.

METHOD OF MAKING PIPE COUPLINGS.

Application filed June 27, 1921. Serial No. 480,581.

To all whom it may concern:

Be it known that I, GEORGE E. MIRFIELD, a citizen of the United States, residing at Youngstown, in the county of Mahoning 5 and State of Ohio, have invented a new and useful Improvement in Methods of Making Pipe Couplings, of which the following is a full, clear, and exact description.

My invention relates to pipe couplings 10 and method of making same. The problem of making pipe couplings at a reasonable cost is not an easy one, and many methods have been used heretofore. One of the usual methods is to take a strip or skelp of muck 15 bar iron or puddle iron and cut it into lengths slightly greater than the circumference of the proposed coupling. This iron is then bent and welded on a mandrel, and the ends are then chamfered and threaded. 20 The loss in this method is high, due to the frequency of poor welds, and may run as high as 20 per cent in small sizes. Furthermore, it requires comparatively expensive material, and the operations during the process 25 of manufacture require a greater amount of labor and handling than in my method presently to be described.

Various other methods have been used, such as making malleable castings and 30 threading and tapping these castings, and also drawing the same from sheet material. Another method is that of cutting seamless tubing into pieces and threading the pieces. Still another is that of drilling couplings 35 from solid bars.

An object of my invention is to provide a coupling which may be inexpensively produced from relatively inexpensive material in such manner as to effect a maximum 40 saving of material, and which will be substantially uniform in structure and appearance, and will therefore better withstand the wear and tear to which such couplings are subjected.

45 My invention relates also to a process by which such a coupling may be made.

My invention will be better understood by reference to the following description taken in connection with the accompanying drawings 50 which illustrate the article and some of the steps in the process for making the same, in which—

Figure 1 shows a section of a blank usually of disk form;

Figure 2 shows a sectional elevation of 55 the blank at the end of the first drawing step;

Figure 3 shows a sectional elevation of 60 the blank at the end of the second drawing step;

Figure 4 shows a sectional elevation of 65 that part of Figure 3 below the line IV-IV;

Figure 5 shows a sectional elevation of 70 Figure 4 after the first drawing step;

Figure 6 shows the blank of Figure 5 with 75 the bottom punched out; and

Figure 7 represents a sectional elevation 80 of a coupling.

Referring to the drawings, a blank 8, 70 usually in the form of a disk, is subjected to a drawing operation, as a result of which the blank takes the form shown in Figure 2, having what may be termed a body portion 9 and a bottom 10. The blank of Figure 2 is then subjected to a further drawing step, resulting in the member shown in Figure 3, having a body portion 11 and a bottom portion 12.

The body member 11 is made of sufficient 85 length to constitute a coupling when the member shown in Figure 3 is severed along the line IV-IV. The member 11 may then be threaded, as shown in Figure 7, by running the threads 6 and 7 all the way through 90 the coupling, or otherwise. The member 12 is shown in Figure 4. This member is subjected to a drawing step and assumes the configuration shown in Figure 5, wherein it has a body portion 13 and a bottom 14. The bottom 14 of the member shown in Figure 5 is punched out and the member 13 is threaded and constitutes a second coupling 95 similar to the coupling made from the member 11 but of smaller diameter.

From the foregoing it will be seen that my process effects a great saving over the usual method of making couplings. By my process the disk may be blanked out of a strip of material which has greater tensile 100 strength than wrought iron, which is the metal usually used heretofore, and therefore my coupling may be made of lighter material, thus effecting a considerable saving in metal. My invention affords a further saving in that the couplings may be drawn from cold metal, and therefore the expense of heating the metal to welding tem- 105

perature is saved. Heated blanks may be used, however, but in such case it will not be necessary to heat the blanks to welding temperature. In fact, in many instances it is preferred to use hot blanks; but the invention is not limited to the use of heat. A further saving is effected by my invention, in that it requires only one operator to attend to two or more machines, each of which 10 performs all of the functions, except threading, necessary in the manufacture of my couplings; whereas heretofore it has been necessary to have an operator for each of six operations used in the manufacture of 15 welded couplings.

From the foregoing, it will be evident that my invention has many advantages resulting from the simplicity of the process and the relatively light material which may be used 20 in making couplings of uniform strength.

In some instances, it may be found desirable to anneal the partially completed articles. If so, this may be done at any point in the method above described.

25 While I have illustrated and described a certain sequence of steps in the process, and have indicated certain kinds of material to be employed, I wish it to be understood that

my invention is not to be limited to the exact number or sequence of steps, nor to the 30 particular class of material indicated; but many detail changes and slight departures may be made from the method as outlined, without departing from the spirit of my invention.

35 I claim:

1. The method of making couplings, which consists in drawing a sleeve of the desired length and diameter from the coupling material, severing a portion of the 40 sleeve with the bottom attached, and drawing a second coupling from said portion, substantially as described.

2. In the method of making couplings, the steps consisting in drawing a sleeve of the 45 desired length and diameter from suitable material, severing a portion of the sleeve with the bottom attached, drawing said portion into cup shape, removing the bottom of the cup, and forming a second coupling 50 from the remaining portion, substantially as described.

In testimony whereof, I have hereunto set my hand.

GEORGE E. MIRFIELD.
